UNITED STATES PATENT OFFICE.

JAMES L. BROWN, OF BROOKVILLE, PENNSYLVANIA.

VENTILATING APPARATUS.

SPECIFICATION forming part of Letters Patent No. 337,368, dated March 9, 1886.

Application filed July 2, 1885. Serial No. 170,507. (No model.)

To all whom it may concern:

Be it known that I, JAMES L. BROWN, a citizen of the United States, residing at Brookville, in the county of Jefferson and State of Pennsylvania, have invented certain new and useful Improvements in Ventilating Apparatus; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 Figure 1 is an enlarged detail of the fastening devices for holding the tube in position and the fly-fan. Fig. 2 is a view, partly in perspective elevation and section, showing the relation of parts and their position. Figs. 20 3 and 4 are views of the regulator. Figs. 5 and 6 are sectional views of the heating apparatus.

This invention relates to improvements in ventilation, and is designed to primarily supply fresh or outside air at any particular 25 point in a room, and also to convey therewith a disinfectant.

The invention is hereinafter fully described and claimed.

30 In the annexed drawings the invention is illustrated as used for a bedroom, and it will be first described for that purpose.

In the drawings, the letter A indicates the window of a room, the bottom sash-rail, a, 35 having an aperture in which is placed a thimble, B; or, if desired, a board fitting the window-frame may be provided with such thimble, and be placed below the lower sash.

Passing through the thimble B is a pipe, 40 (flexible or rigid,) C, the outer end, c, of which opens into the air and the inner end, c', into a fan-box, D, conveniently placed at the window A. This fan-box may be of any of the well-known constructions, no claim being 45 made to any special construction, and having the fan E, run by spring or other motor. This box D has an outlet, d, to which is connected a piece of tubing, F, secured to the T or three-way pipe G. One end, g', of this pipe is 50 connected to the tubing F, another, g'', to another piece of tubing, H, and a third, g,

provided with a cock, g³, leads into a bottle or receptacle, I, wherein is placed some suitable disinfectant or antiseptic. The tubing H passes from pipe G to the bed K, where it 55 may rest on the head-board k, as shown, and is there held by the bracket L. This bracket L consists of the sleeves l l, by which it is secured in place—say to the bed-posts k' k'—and the adjustable holder l'. This holder is hinged 60 at l² to the sleeves, and is secured adjustably by thumb-screws l⁴ l⁴, which engage the slots l³ l⁵ in the curved arms l⁶ l⁶.

Sleeved on the cross-bar l' of the holder l' is a thimble, M, having the cross-passage m, 65 through which passes and snugly fits the tubing H. This thimble is adjustable on the bar l', and can be placed at any point.

At the end h of the tubing H is secured an eccentric clamp, N, having the handle n, and 70 held on the tubing by a sleeve, n', provided with a hinged plate, n², on which the eccentric bears. Instead of the eccentric a simple valve, N', may be placed in the tubing. Either form makes a regulator for determining the 75 supply of air.

On the holder l' is held a fly-fan, O, by a sleeve, p, on the arm p'. This arm p' has the stem s journaled at its end and carrying the wings s' s' below and the box s² above, said 80 box being open at the top and having the inclined vanes s³.

Instead of making the holder l' of one rigid piece, as shown in Fig. 2, it may be made with its sides q q, having eyes q' q', into which the 85 front or bar l' is slipped. This latter arrangement adapts the bracket for beds of different widths.

In use the thimble M is placed on the bar l' at the proper point to bring the end h of tubing H over the occupant of the bed, and the bracket L is adjusted so as to place the holder l' at the proper angle for said end h to be at an agreeable height. The fan E is put in operation, and air drawn from the outside is 90 forced out at end h just at the point where it is required. The tubing H is preferably flexible, for ease in use and adjustment. The eccentric N can be turned by the occupant of the bed, reducing the size of the opening at 95 the end h, and thus regulating the supply, or the valve N, whichever is used. At a proper

point a gauze or other strainer may be placed, to prevent dust, &c., from passing through the tubing. If the occupant of the bed be sick, and a disinfectant is needed, the cock g^3 can be opened and a supply will pass with the air-current. If desired, as not necessary, the bottle I need not be used at all, and a single tube may pass from the fan to the bed. When desired, the fan O is put in place and adjusted so that the box s^2 is under the end of the tubing H. The air striking the vanes s^3 turns the fan. Thus the occupant of the bed is not only cooled, but flies are kept away; also, the wings s^1 throw the outgoing air about, and it strikes the person diffusedly and gently.

For preserving corpses an antiseptic may be placed in the receptacle I.

This invention is not only of value for persons in normal health, but it is specially of great value for sick persons. The fresh air is brought from outside direct to the patient without any draft or danger of cold, and is supplied as needed. In cases of wounds the air can be directed to the injured place, thus taking the place of cold water, and is more efficacious.

This device can be used in other places than bedrooms, in fact at any point, especially where persons have to stay long at one particular spot, and when other methods of ventilating would induce a draft.

The apparatus is movable, and can be carried from place to place and located anywhere. All that is needed is connection with the outside of the building by a window, door, or otherwise.

In addition to the device already set forth for furnishing fresh air I propose to add means for introducing to the body of an invalid warm or medicated air, or for warming a bed. The pipe G is to be made so that the end g^2 shall fork, a suitable coupling, t, being used, the portion g^2 connecting with the tubing H, as already described, and the portion t' connecting with a tubing, T, which passes off to the bed and can be introduced under the covering.

The tubings H and T are each provided with a clamp—such as shown in Figs. 3 or 4—so as to throw the current in either direction. At a suitable point in its length the tubing T is connected with a tubular box, V, the latter being part of said tubing. This box V is of metal, and is held to the tubing on each side by a thimble, v, composed either of wood or asbestos, or an asbestos sleeve, v', with a wooden one, v'', within it. The box V is held by a suitable support, W, to which it may be secured. This support W consists of a base, w, and several legs, w', rising therefrom, such legs being adjustable, as shown in Fig. 5. On the under side the box V is provided with a flaring hood, B', larger at the bottom. Where this hood joins the body of the box the latter has an opening, b', and is

provided within with a flaring lip, b², which partially projects over the opening from one side, as shown in Fig. 5. The box may have an enlargement, b³, on top, so that the presence of the lip b² shall not diminish the volume of the air.

In using this part of the device a lamp, B², is placed on the base w, with the top of its chimney at the hood B' and just under the opening b', its relative position being varied by adjusting the legs w'. By lighting the lamp and admitting the current of air from the fan E through the pipe t the heated air rising through the opening b' is carried off to the bed.

Instead of using the device in Fig. 5 that shown in Fig. 6 may be used. Here the box V' has no opening above the lamp. On top it supports by legs c' c' a reservoir, C', from which a pipe, c², having a tap, c³, descends, and enters into the box V' about on a line with the place for the lamp beneath.

Water, alcohol, or other liquid may be placed in the reservoir C', and being admitted into the box V' is vaporized and passes to the bed. The devices shown in these two figures are therefore generators, wherein are formed hot air or vapor, which can be used as desired.

Having thus described my invention, what I claim is—

1. The combination of the window having a suitable aperture, the fan, and the inlet and outlet pipes or tubing, the latter having a flexible extension, as set forth.

2. The combination of the window having a suitable aperture, the fan, the inlet and outlet pipes or tubing, and an adjustable bracket for the outlet-pipe, as set forth.

3. The combination of the fan, the inlet-pipe, the outlet pipe or tubing, and the T or three-way pipe located in the outlet pipe or tubing, and having a cock placed as described, with a receptacle placed at that end of the three-way pipe which has the cock, as set forth, with the vessel I located at the T-pipe, as and for the purpose set forth.

4. The portable ventilating apparatus consisting of an inlet, a fan, and an outlet-pipe, the last having a flexible extension, as set forth.

5. A ventilating apparatus, in combination with a fly-fan located at the end of the educt of such apparatus, as set forth.

6. The combination of a fan, an induct, an educt, and a flexible extension to the latter, and a metallic boxing forming a part of said educt, whereby the air passing through the educt may be warmed by placing a lamp or other heater under such boxing, as explained and set forth.

7. In a ventilating apparatus, the fan, and its induct and educt, the latter provided with a metallic boxing, in combination with a reservoir above such boxing, and having a pipe leading into or within such boxing.

8. In a ventilating apparatus, the fan, and its
induct and educt, the latter having a flexi-
ble extension, which is provided with a me-
tallic boxing, in combination with a reser-
5 voir above such boxing, and having a pipe
leading into or within such boxing, as set
forth.

In testimony whereof I affix my signature
in presence of two witnesses.

JAMES L. BROWN.
